METHOD OF REFORMING ANGLE BARS

Lawrence S. Wilbur, Chicago, Ill., assignor to
 Carter Blatchford, Inc., Chicago, Ill., a corpora-
 tion of Illinois

Application August 3, 1939, Serial No. 288,109

4 Claims. (Cl. 29—169)

My invention relates to angle bars which are used for splicing or fastening rails, and is more particularly directed to the reformation of worn angle bars to be used for splicing new or worn rails. To that end the invention relates to the conversion of the head contact type of angle bars into the head free type of angle bars which possess exceptional advantages as splices for either new or worn rails.

10 Rail joint angle bars are used generally by railroads for splicing sections of rails and the constant pounding by heavy traffic and load conditions on the rail heads at or near their spliced ends causes considerable wear upon the top of the angle bars, where the rail heads bear. The greatest proportion of wear occurs on the top portion of the angle bars which necessitates frequent tightening of the bar bolts. By tightening the angle bar bolts, the angle bars on both sides 20 of the rails are drawn toward each other and exert a wedging action relative to the underside surface of the rail head and the top surface of the rail foot.

As the top portion of the angle bars wear and 25 become loose they are pulled toward the rail web to compensate for the wear. When they bottom against the web no further wedging action is obtainable and the angle bars then require replacement. The undersides of the rail heads are subjected to some wear but the greatest proportion 30 is borne by the angle bars, particularly at their medial portion.

It is sometimes the practice to cut off the worn 35 ends of the rails and splice such cut rails with new or reformed angle bars, the latter being reformed to provide a straight top edge having a uniform head contact with the undersides of the heads of the cut rails. Another practice is to reform the worn angle bars to provide a longitudinally crowned top edge to fit the undersides of 40 the heads of the worn rail ends.

There are objections to both practices from 45 the standpoint of discarding portions of still usable rails and the inability to use the reformed angle bars with new or differently worn rails. Accordingly, it is an important object of this invention to provide a method for converting worn 50 angle bars into the head free type of angle bar which takes its loading engagement in the rail head fillet thereby using an entirely new bearing surface unaffected by previous wear. This method eliminates the need of cutting off worn rail ends and compensates for wear on the undersides of rail heads if the ends are not cut off, and 55 provides a reformed angle bar having a greater

angular loading engagement thrust between the rail head and the rail foot than the head contact type of angle bar. This angular loading engagement provides greater stability and strength which effectually keeps the rails in proper alignment and provides for further take up to compensate for later wear which occurs between the contacting portions of the angle bar and the rail.

Other objects of the invention will more fully appear from the following detailed description 10 taken in connection with the accompanying drawing, which illustrates the embodiments thereof, and in which:

Figure 1 is a vertical cross-section, with parts 15 in elevation, illustrating a pair of my reformed headfree rail angle bars bolted in position relative to a rail;

Figure 2 is a fragmentary vertical cross-section 20 illustrating, in full lines, a head contact type of rail angle bar as applied to a rail, with the dotted lines indicating a finished headfree type of bar;

Figure 3 is a vertical sectional view illustrating, 25 in dotted lines, the initial step in the reformation of a head contact type of bar to a headfree type of bar;

Figure 4 is a view similar to Figure 3, illustrating 30 the second step in the method of my invention;

Figure 5 is a view similar to Figures 3 and 4, 35 illustrating the final step in the method of reforming rail angle bars according to my invention, the dotted lines indicating the outline of the finished headfree bar similarly shown in Figure 2.

Any of several practices may be resorted to for converting a head contact type of angle bar into a head free type of angle bar, as indicated in Figure 2, including hot pressing operations 40 with dies which is a practice used in the present instance. It should be understood, however, that the several steps referred to in the reformation of angle bars in accordance with the method of my invention are used merely for the purpose of illustration, and, actually the various 45 steps take place virtually simultaneously.

As shown on the drawing:

In Figure 1, the reference numeral 5 designates a rail to which is applied a pair of reformed angle bars 6. These angle bars 6 are drawn into a wedging position by a bolt 7 which is tightened, as the top surface of the angle bars wear, by a nut 8 locked against a washer 9.

Each of the reformed angle bars 6 consists of 55

a web portion 11, a head portion 12 and a foot flange portion 13, and the metal distribution of these three elements are substantially maintained in the reformation operation in order that the 5 loading and deflection forces may be distributed properly.

Illustrated in Figure 2 in full lines, is a worn angle bar 6a as applied to the rail 5, which discloses the full head contact between the top 10 surface 14 of the angle bar head 12a and the underside surface 15 of the rail head 16. The web 11a connects the angle bar head 12a and the angle bar foot flange 13a, which flange engages the foot flange 17 of the rail at the engaging surfaces 18 and 19. While the web 11a of Figure 2 is disclosed substantially parallel to the center line of the rail 5, it should be understood that other types of head contact angle bars may be reformed by the method of my invention where the web 11a may lie in inclined position when applied to the rail.

As the top surface 14 of the angle bar head 12a wears, the wear is compensated for by drawing the angle bar 6a bodily inward by the sliding engagement between the top and bottom surfaces of the angle bar and the complementary surfaces of the rail 5. This is accomplished by tightening a bolt arrangement similar to that illustrated in Figure 1. By drawing the angle bar 6a inwardly 25 a wedging action results relative to the complementary rail. This wedging action is limited by the rail web, for when the angle bar head 12a engages the rail web further travel of the angle bar inwardly is impossible.

The dotted lines, of Figure 2, indicate the outline of the reformed or finished headfree type 35 of rail angle bar. This diagrammatic view serves as an illustration of the comparison of the rail angle bar both before and after the reformation thereof by the method of my invention. The dotted outline of the re-formed angle bar is shown in full lines in Figure 1.

Referring to Figure 3, the dotted lines indicate the outline of the primary step in the operation 45 of reforming a head contact type of bar. This step serves to rotate the angle bar head 12a outwardly around an axis 20, which axis is located on the top of the outer face 21 of the web 11a and which extends along the length of the angle 50 bar. As shown in Figure 3, an angle 22 is thereby formed between the top surface 14 of the angle bar head 12a and the underside surface 15 of the rail head 16. This angle 22 results in the freedom of the head 12a from contact with the underside 55 of the rail head 16. While the angle 22 may vary depending upon the type of and wear on the angle bars to be reformed, I have found generally an angle of 2° to 4° is sufficient for most practical purposes and one which gives the best results.

Figure 4 illustrates a further step in the conversion of a rail angle bar according to this invention. The partly converted angle bar 6b of Figure 3 is illustrated in Figure 4 in full lines. In carrying out this step, the web 11a is displaced inwardly to a position as indicated by 11b. Simultaneously, the outer face 21 of the web is straightened to form the flat face 21a. During this operation, the exterior angle which is formed by the top surface 14a of the angle bar head and the web faces 21 and 21a remain unchanged. In other words, the angle bar head is not revolved but is displaced transversely of its former position. This step also serves to slightly elongate 70 the web 11b, depress the foot flange as indicated at 13b and to lengthen the foot flange as indicated at 23.

It should be understood at this point, that these die pressing operations perform not only bending but sufficient displacement of metal to form the angle bar in each step as outlined by the dotted lines. In no case is the displacement 5 of metal of such a substantial nature as to affect the structural loading capacity of the angle bar.

Figure 5 illustrates the finishing step of converting the worn out angle bar to a headfree type of bar while the bar is still hot. The partially 10 converted angle bar 6c illustrated in Figure 4 in dotted lines, is illustrated in Figure 5 in full lines. The final reforming step serves to tilt the angle bar foot flange 13b upwardly to a position 15 as indicated at 13c. This upward tilting increases 18 the exterior angle of the outer bolting face 21a and the newly inclined underside surface 18a of the foot flange. By increasing this exterior angle an increase in the clearance at the point 24, between the underside surface of the angle bar foot 20 flange and the upper inclined surface 19 of the rail flange, is provided to facilitate inward and upward adjustments of the foot flange of the bar, as clearly shown in Figure 2. This operation also serves to decrease the bearing surface 18 immediately adjacent the clearance 24. Simultaneously with the tilting of the foot flange, the metal on the lower inner corner 25 of the angle bar head is displaced diagonally upward and inward to reform the upper inner corner 26 of the head 30 into a rounded bearing element 26a adapted for bearing engagement in the curved seat 27 provided by the rail head fillet.

As clearly shown in Figure 2, the resulting head-free type of angle bar engages the complementary rail in the upper bearing fillet seat 27 at 35 the top, and on the upward slidable bearing engagement foot flange 13c, as at 18, on the bottom or foot thereof.

One of the structural advantages obtained by 40 using a headfree type of angle bar is the diagonal centerline of the loading engagement thrust which stabilizes and strengthens the rail to keep it in gauge and surface alignment. As illustrated in Figure 2, the center line of the loading engagement 45 thrust of the head contact type of angle bar is substantially normal to the head contacting surfaces while in the headfree type of angle bar it is angularly spaced at a greater inclination relative to the vertical axis of the rail than in 50 the head contact type of bar.

The final shape of the reformed headfree type 55 of angle bar provides an outer bolting face 21a in vertical parallel spaced alignment with the vertical axis of the rail which insures a full contact with the clamping bolt head and nut to facilitate the even drawing of the angle bars toward each other. As the bearing within the rail fillet wears, the tightening of the bolt causes the foot flange of each bar to slide upwardly on the 60 inclined foot flange of the rail to adjust for such wear and retain the wedging action against the rail head.

From the foregoing description it will be apparent that this method of reforming angle bars 65 is directed to a feature of displacing metal of the angle bar head from a free portion thereof to a bearing corner without in any way weakening the structure thereof. My method of reforming angle bars involves the feature of increasing 70 the exterior angle between the outer bolting face 21 and the plane of the inclined underside surface 18 of the rail foot flange. Likewise, the exterior angle between the outer bolting face 21 and the top surface 14a of the angle bar head is 75 increased.

Although the form of rail joint angle bars may differ the essential steps in reforming such bars will be substantially those described herein, resulting in the production of headfree types of bars having the structural advantages that appear in the foregoing description.

It will, of course, be understood that various details of construction may be varied through a wide range without departing from the principles of this invention and it is, therefore, not the purpose to limit the patent granted hereon otherwise than necessitated by the scope of the appended claims.

I claim as my invention:

- 15 1. The method of reforming an angle bar for rail joints by a pressure reshaping operation which comprises rotating the head of the bar toward the outer face of the bar and relative to the web of the bar to move the rail head contact portion of the bar head away from rail head contact position, flowing metal from the lower inner corner portion of the bar head to move metal inwardly from the normal inner top corner of said head for creating a rail fillet engaging portion, and moving the web of the bar relative to the foot portion thereof to place the outer face of the web in a vertical position when applied to a rail.
- 20 2. The method of reforming rail joint angle bars having foot flanges overhanging the base of the rail by a pressure reshaping operation which comprises rotating the head of the bar toward the outer face of the bar and relative to the web of the bar to move the rail head contact portion of the bar head away from rail head contact position, moving the web of the bar rela-

tive to the foot portion thereof to place the outer face of the web in a vertical position when applied to a rail, elongating the web, flowing metal from the lower inner corner portion of the bar head to move metal inwardly from the normal inner top corner of said bar head for creating a rail fillet engaging portion, and tilting the overhanging portion of the foot flange to increase the exterior angle between the outer face of the web and the bottom of the overhanging flange portion without disturbing the exterior angle between the outer face of the web and the rail engaging foot portion.

3. The method of reforming an angle bar for rail joints by a pressure reshaping operation which comprises rotating the head of the bar toward the outer face of the bar and relative to the web of the bar to move the rail contact portion of the bar head away from rail head contact position and moving the web of the bar relative to the foot portion thereof to place the outer face of the web in a vertical position when applied to a rail while maintaining the head in said rotated position relative to the web.

4. The method of reforming an angle bar for rail joints by a pressure reshaping operation which comprises rotating the head of the bar toward the outer face of the bar and relative to the web of the bar to move the rail head contact portion of the bar head away from rail head contact position, and flowing metal from the lower inner corner portion of the bar head to move metal inwardly from the normal inner top corner of said head for creating a rail fillet engaging portion.

LAWRENCE S. WILBUR.
